(No Model.)

F. PRINZ.

MIDDLELINGS PURIFIER.

No. 267,716.

Patented Nov. 21, 1882.

UNITED STATES PATENT OFFICE.

FAUSTIN PRINZ, OF DUNDAS, MINNESOTA.

MIDDLENS-PURIFIER.

SPECIFICATION forming part of Letters Patent No. 267,716, dated November 21, 1882.

Application filed July 23, 1881. (No model.)

To all whom it may concern:

Be it known that I, FAUSTIN PRINZ, a subject of the Emperor of Germany, and a resident of Dundas, in the county of Rice and State of Minnesota, have invented certain new and useful Improvements in Middlens-Purifiers, of which the following is a specification.

This invention relates to machines for purifying middlings; and it consists in the construction and combination of parts, hereinafter particularly described, and then specifically defined by the claims.

I attain my proposed objects by the use of the mechanism illustrated in the accompanying drawings, in which—

Figure 1 is a side elevation, partially in section, and Fig. 2 is a cross-sectional view. Fig. 3 is a detail view of the feed-plate; Figs. 4, 5, and 6, enlarged detail views of the wiping-strip; Fig. 7, perspective view detached of a portion of one end of the double shaker and hopper frames, illustrating the manner of constructing them and arranging an air cut-off. Fig. 8 is an enlarged detail view of a portion 25 of one of the shaker-frames, illustrating the manner of securing the cloth thereto.

A is the frame-work, made in any desired manner, and provided near the top with a shaker-frame, B', supported upon springs a, 30 and adapted to be vibrated by an eccentric, b, as shown. Beneath this shaker-frame B' is a second shaker-frame, B², and beneath the second shaker-frame is a similarly-shaped frame, B³, in which hoppers c' c² c³ c⁴ are arranged to 35 convey the middlings after it leaves the shakers into the separating apparatus. All three of the frames B' B² B³ are connected together at suitable intervals by straps e, so that they will all vibrate together. The lower ends of 40 the springs a are connected to hangers d' by bolts d², passing through slots in the springs, so that the latter may be adjusted higher or lower by a set-screw, d³, to alter the inclination of the frames B' B² B³. The hangers d' are provided with ribs d⁴, adapted to fit into corresponding grooves in the springs, (see small detached perspective view at the right of Fig. 1,) so that no side motion will be permitted to the springs.

E is a thin, flat, slightly-inclined plate, at-

tached by one end and its sides to the upper end of the upper shaker-frame, B', beneath the feed-spout F, which thus forms a feed-plate over which the "chop" is fed in an even, regular stream. Across the frame B', above the lower end of this feed-plate E, is a bar, g', through which a screw, g², passes and is connected to the lower edge of the plate E, so that by turning the screw up or down the plate E may be drawn up in a curve, as shown in Fig. 60 3, or allowed to assume a horizontal position to regulate the flow of the chop, as hereinafter shown.

About one-third of the cloth of the upper shaker, B', will be of a rather fine mesh, while 65 the middle third will be of coarser mesh, and the "tail" third will be of a still coarser mesh.

The second shaker-frame, B², is provided with boards or chutes h' h² h³ above its cloth, and with their upper ends beneath the points of division of the different numbers of the cloth of the upper shaker. The second shaker-frame B² is also covered with three or more numbers of cloth similar to the upper shaker, B', while the lower ends of the chutes h' h² h³ are adapted 70 to deliver the middlings that fall through the shaker-frame B' at the proper points upon the different sections of cloth of the lower shaker-frame, B², as hereinafter explained.

The hoppers c' c² c³ c⁴ are arranged similar 80 to those shown in my application for patent, No. 11,546, filed June 11, 1880.

Beneath each of the shakers B' B² are wooden trough-shaped strips i' i², arranged to slide back and forth from side to side of the machine upon rods i³. (See Figs. 1, 4, 5, and 6.) Within these trough-shaped strips smaller flat wooden strips i⁴ are set and held up against the cloth by springs i⁵, so that when moved back and forth across the machine the upper strips, 85 i⁴, will rub against the cloth and remove the adhering dust therefrom.

i⁶ is a large sheave or cord-pulley attached to the side of the machine outside of and opposite to the center of the shakers B' B², and of a size equal to the space between the lower sides of the shaker-frames, so that if a cord, i⁷, be attached to the center of the trough i' beneath the upper shaker, B', and carried around the sheave i⁶ and back to the trough i' beneath 90 95 100

the lower shaker, B², the two lengths of cord will be parallel with each other, as shown in Fig. 2.

i⁸ i⁹ are two smaller sheaves or pulleys attached opposite to the centers of each of the shakers B' B² and on the other side of the machine from the sheave i⁶, while a fourth pulley, i¹⁰, is attached to the machine near the bottom and on a line beneath the pulleys i⁸ i⁹, so that the cord i⁷ may be continued on over the pulley i⁸ from the upper wiper, down around the pulley i¹⁰, and up over the pulley i⁹, and thence into the lower wiper. By this arrangement it will be seen that if the cords between the pulleys i⁸ and i⁹ and pulley i¹⁰ be pulled up and down the wipers will be drawn back and forth beneath the shakers.

Outside the machine, near the lower part, is a gear-wheel, k', mounted upon a shaft or stud, and adapted to be revolved by a pinion, k², upon another stud, carrying a ratchet-wheel, k³, the pinion and ratchet being adapted to be revolved together.

k⁴ is an arm, pivoted at k⁵ to the side of the machine, and connected at k⁶ to one of the lengths of the cord i⁷ running between the pulleys i⁸, i⁹, and i¹⁰, and provided at the other end with a slotted arm, k⁸.

The gear k' is provided with a crank-pin, k⁹, which fits into the slot k¹⁰ in the arm k⁸. When the gear k' is revolved its pin k⁹ will not affect the arm k⁸ while running through the slot; but (the length of the slot being less than the diameter of the revolution of the crank-pin) when it strikes the upper or lower ends it will raise or lower the arm k⁸ and lever k⁴ and leave them stationary for some time at both the upward and downward strokes, or while the crank-pin is passing through the slot k¹⁰.

40 The troughs i' will be so placed that they are upon opposite sides of their respective shaker-frames, as shown, so that if the length of the cord i⁷ running over the pulleys i⁸ or i⁹ be pulled up or down by the arm k⁴ the wipers will be drawn back and forth beneath the cloth. The wipers will be so arranged that they will be drawn out beyond their respective shaker-frames at the end of each stroke, and remain outside during the time of their 45 "rest," so that they will present no obstruction to the flow of the middlings. Small holes will be formed through the bottoms of the troughs i' to permit the escape of the middlings that may work in beneath the wiping-strips. Rubber tubes or plates, bristles, fur, sheep-skin, or any other suitable material may be used instead of or attached to the wiping-strips i⁴, if desired. By thus attaching the shaker-frames and wipers to each other, so that they vibrate 50 together, no horizontal friction occurs between the cloth and wipers except in passing from side to side. Hence at least one-half the wear on the cloth is prevented and the cleaning accomplished in an equally satisfactory manner.

65 This is a very important feature, as it reduces very materially the wear and friction upon the expensive bolting-cloth.

Beneath the frames B' B² B³ are arranged two cases or boxes, G' G², having open central spaces and chutes and wings m' m² m³ m⁴, 70 arranged similar to those shown in my application for a patent, No. 11,546, filed June 11, 1880, above referred to, except that the angular chutes m³ are cut away at their inner ends to form hopper-shaped cavities between them 75 and the inner inclined chutes m², to assist the middlings in falling through.

H' H² are two frames, adapted to be raised and lowered and set inside the casings G' G² between the chutes m² and central open spaces, 80 and provided with cross slats or bars m⁵, adapted to fit up against stops m⁶ on the chutes m², so that when the frames H' H² are lowered down open spaces will occur between the cross-bars m⁵ and stops m⁶, through which the air 85 passes, and when the frames H' H² are raised up until the cross-bars m⁵ come in contact with the stops m⁶ the air-currents may be entirely cut off; or by adjusting the frames H' H² up or down the force of the air-currents may be 90 easily regulated and controlled.

Beneath the casings G' G² three conveyers, G³ G⁴ G⁵, are arranged, the central one being connected by hoppers, &c., with the dust-collectors, while the side ones are connected with 95 the middlings-hoppers, by which the middlings and dust may be removed from the machine. Spouts or other devices may be substituted for the conveyers, if desired.

Across the center of each of the cases G' G² 100 are dust-collecting balloons G⁶ G⁷ and fans I' I², arranged as in my application for a patent, No. 37,281, filed July 7, 1881.

Along the edges of the shaker-frames B' B² pins n' are inserted, (see Fig. 8,) and through the 105 edges of the bolting-cloth binding n² eyelets are formed, through which and over the pins n' a cord, n³, is alternately run and adapted to be drawn taut, and thus stretch the bolting-cloth upon the shaker-frames. This is a 110 very convenient and thorough manner of securing the cloth, as it not only stretches every part equally, but allows it to be readily and easily tightened when it has become slack, and without removing the shaker-frames from the 115 machine or disfiguring the cloth or frames with tacks or nails.

The spaces between the shaker-frames may be provided with hoods t, (see Fig. 7,) so that the air may be shut off at these points and 120 forced to pass upward through both shaker-frames, as under some circumstances this may be found necessary.

Across the frame A, above the shaker-frame B', are one or more air-trunks, L' L², provided 125 with extensions L³ L⁴, leading downward and into the casings G' G² between the balloons G⁶ G⁷, and having open lower sides connected to hoods B⁴ B⁵ upon the shaker-frame B' by loose cloth joints v' v², so that the vibrations 130 of the shaker-frames and hoods will not affect the trunks. By this arrangement a current of air may be drawn up through the shaker-frames by the same fans, I' I², that furnish the currents

for the dust-collecting balloons $G^6 G^7$, and doing away with the necessity of extra fans being arranged for the shaker-frames.

The first section of the cloth upon the upper shaker-frame, B' , from y^1 to y^2 , as before described, is covered with bolting-cloth of a rather fine mesh, usually about No. 5, while the remaining two sections, from y^2 to y^3 and from y^3 to y^4 , are covered with cloth of an increasing degree of coarseness, usually about No. 4 and No. 2, respectively, while the lower shaker-frame, B^2 , is similarly covered with sections of cloth $y^5 y^6$ and $y^6 y^7$ and $y^7 y^8$, of an increasing degree of coarseness from the "head" to the "tail," usually Nos. 6, 5, and 4, the upper section, $y^5 y^6$, being the finest in the machine.

The chop is fed to the first shaker-frame, B' , over the feed-plate E , which, by means of its delicate adjustment, may be so set with reference to the machine as to feed the chop in a regular, even stream over the whole width of the shaker-frame. The middlings is then caused by the rapid vibratory motion of the shaker to flow down over the bolting-cloth, the finer heavier particles sinking to the bottom, the larger lighter particles rising above them, while the fine bran and dust rise to the surface. The particles of middlings finer than the meshes of the first cloth, $y^1 y^2$, fall through and are conveyed by the chute h' to the upper end of the first section, $y^5 y^6$, of the second shaker, B^2 , over which it flows, and its particles finer than the cloth upon this section fall through and are conveyed by the hopper c' to the first set of separating-chutes, $m' m^2 m^3 m^4$. Some of the fine middlings that should pass through the first section, $y^1 y^2$, of the upper section of the shaker B' will usually be carried over upon the second section, $y^2 y^3$; and to convey these back upon the first section, $y^5 y^6$, of the second shaker, B^2 , the second chute, h^2 , is extended at its lower end to overlap the section $y^5 y^6$, and thus convey all the middlings that fall through the section $y^2 y^3$ upon the section $y^5 y^6$, where the fine middlings that have escaped the section $y^1 y^2$ will be sifted through into the hopper c' , while the particles too coarse for section $y^5 y^6$ will be sifted through section $y^6 y^7$. The chute h^3 will overlap the section $y^6 y^7$ in the same manner as the chute h^2 overlaps the section $y^5 y^6$, to convey the middlings that are fine enough for the section $y^2 y^3$, but that have been carried over upon the section $y^3 y^4$, to section $y^6 y^7$, where they belong. By this arrangement the middlings are very evenly graded as to size, so that in passing down through the zigzag separating-chutes $m' m^2 m^3 m^4$ each section of chutes will be supplied with middlings of a uniform size. Hence a more perfect action of the air-blasts may be secured and a better quality of middlings. This arrangement also secures a very large extent of cloth-surface without enlarging the machine, which is a very desirable advantage in mills which are cramped for room. The middlings passing down over the zigzag chutes $m' m^2 m^3$

m^4 are subjected to the inwardly-flowing currents of air, the dust and adhering bran, &c., removed therefrom, and the clean middlings only delivered to the conveyers, the dust-laden air at the same time being carried through the dust-collectors and purified. The bran and heavy dust are carried over the tail z' of the upper shaker, B' , while the very coarse middlings and "tailings" of the second shaker only find their way to the fourth hopper, c^4 . The blast of air through the trunks $L' L^2$ will be just sufficient to exert a slight lifting effect upon the bran, &c., and not sufficient to carry it upward. Thus only the very finest dust will be carried off by the trunks into the casings $G' G^2$.

What I claim as new is—

1. In a middlings-purifier, the combination, with a shaker-frame and a hopper, of an intermediate feed-plate connected at its sides and one end to the shaker-frame, and at its lower end to an adjusting-screw, whereby the plate is adapted to vibrate with the shaker-frame and be adjusted from its center to its sides, substantially as and for the purpose set forth.

2. In a middlings-purifier, the combination of a vibrating bolting-cloth frame and a wiping or brushing device for removing the dust from the cloth, adapted to be reciprocated across the bolting-cloth at right angles to the flow of the middlings thereover, and to be vibrated therewith and drawn out beyond the sides of the shaker-frame, substantially as and for the purpose specified.

3. In a middlings-purifier, the frames B' , B^2 , and B^3 , arranged one above the other, connected together, and provided with chutes and hoppers, so that the middlings may pass from one frame to the next, in combination with the feed-plate E , connected at its sides and one end to the upper shaker-frame and its lower end to an adjusting-screw, and a single shaft and eccentric for vibrating the feed-plate and a series of frames, substantially as set forth.

4. In a middlings-purifier, the combination of a shaker-frame provided with a hood, a casing beneath the shaker-frame, a dust-collecting balloon located therein, a tube or flue having a flexible connection to the hood of the shaker-frame and leading therefrom into the balloon-casing, and a fan, located substantially as described, whereby the several parts will operate as set forth.

5. The combination of the shaker-frame B' , trough-shaped strips i' , strips i^4 , springs i^5 , and rods i^6 , substantially as set forth.

6. The combination, with the shaker-frame B' B^2 and cloth cleaning-strips $i' i^2 i^4$, of the rods i^3 , sheaves $i^{10} i^6 i^8 i^9$, cord i^7 , operating-levers $h^4 h^8$, and gears $h^5 h^9$, substantially as set forth.

7. The combination, with frame a , hanger d' , formed with a tongue, and shaker-frames B' B^4 , of spring a , provided at its lower end with a groove fitted to the tongue on the hanger d' , and a screw, d^3 , by which said spring is ren-

dered vertically adjustable, substantially as set forth.

8. The combination of chutes m' m^2 m^3 m^4 , adjustable frames H' H^2 m^5 , steps m^6 , dust-collecting balloons C' , and fans I' I^2 , substantially as set forth.

9. The shaker-frame of a middlings-purifier, provided with pins n' , in combination with the bolting-cloth provided with eyelets, and a cord

passing over the pins and through the eyelets, substantially as and for the purpose set forth.

In testimony whereof I have hereunto set my hand in the presence of two subscribing witnesses.

FAUSTIN PRINZ.
